UNITED STATES PATENT OFFICE.

AUGUST J. KEMPIEN, OF ST. PAUL, MINNESOTA.

GAME APPARATUS.

1,162,054.

Specification of Letters Patent. Patented June 30, 1914.

Application filed June 7, 1913. Serial No. 772,286.

To all whom it may concern:

Be it known that I, AUGUST J. KEMPIEN, a citizen of the United States, residing at St. Paul, in the county of Ramsey and State of Minnesota, have invented a new and useful Improvement in Game Apparatus, of which the following is a specification.

An object of this invention is to provide an improved game apparatus for use in playing the game of what is commonly called "paddle wheel." Heretofore it has been customary to play this game of chance with a set of paddles made out of wood and having a group of numbers imprinted upon their surfaces, each group being different from the group on any other paddle and to use the paddles over and over for playing a number of games. This idea of using a permanent paddle is objectionable because the paddles become soiled and unsanitary and there is always delay experienced between games by the non-return of one or more of the paddles to the operator immediately after a game has been played.

With my invention I overcome these objections by the use of printed tickets which can be used for advertising purposes and which are not necessarily returned to the operator after a game has been played. In order to prevent cheating, the tickets for one game are supplied with a key which prevents their use for playing any other game.

Further features of advantage will be apparent from the following description in which the drawing forms part thereof.

In the accompanying drawing, Figure 1 is a perspective of a book of tickets which embody my improvements and which are employed for playing the game of chance to which my invention relates; Fig. 2 is a plan of the wheel of chance which is also employed in playing the game and Fig. 3 is an alternative construction of a series of tickets for playing a game.

The game apparatus comprises one or more groups or sets of tickets, each group or set consisting of a series of tickets such as 2 to 13 inclusive indicated in Fig. 1, and each ticket bearing a group of numbers or symbols, such as A and a key indicated by a serial number such as B, all of which are printed or otherwise inscribed upon the surfaces of the tickets. These tickets may be in the form of a leaf perforated such as at C whereby the tickets may be easily segre-

gated by tearing upon the perforated lines. The numbers on the tickets, any one of which indicates a winner may be printed in serial order allotting a group to each ticket. For instance the numbers may run from 1 to 48 and a group of four be allotted to each ticket, the various groups being numbers in selected fixed order or at random. The leaves of tickets may be bound in book form, the stub end I of each leaf being inscribed with the serial number D corresponding with the serial number B which is printed upon each ticket. These serial number stubs are detachable upon the perforated line 14 on the back 15 of the book.

The chance wheel illustrated in Fig. 2 is of ordinary construction and consists of a wheel frame E journaled at F on the support G, it being provided with a plurality of pins 16, equally spaced apart near its periphery, the spaces between the pins being numbered consecutively, said numbers corresponding with the numbers on the tickets which are used in playing each game. For instance the number of spaces on the wheel illustrated are forty eight and the number of digits appearing on the tickets illustrated in Fig. 1 for playing a single game correspond. A flexible indicating stop 17 is mounted upon the stud 18 on the frame or support G with its free end adapted to sweep over the pins 16 as the wheel is revolved or spun.

The operator of a game distributes the series of tickets to the players, it being obvious that any number of the leaves of tickets for a number of games may first be distributed. The serial number of the game which is about to be played is then called or posted and the wheel spun, the lucky number at which the wheel stops indicating the winning number. The person holding the ticket upon which the winning number is printed is then declared to be a winner. The stub I is then torn away and another game played, the succeeding serial number being called or posted in advance by the operator. The speed at which the games may be played is greatly increased by the use of my improved apparatus. The winning and serial number corresponding may also be posted in case the winner is absent when called. It is also a marked advantage to be able as with my improved apparatus to sell a number of sets of tickets in advance of the time when games are to be played for in-

stance at a fair where money is being raised through the selling of tickets, solicitors may in advance sell a large number of tickets pertaining to a number of different games 5 without danger of fraud on the part of those holding tickets, it being obvious that the key to the tickets prevents the misuse of any ticket for the purpose of claiming a prize.

It is not necessary to assemble the tickets 10 in book form, it being obvious that separate and distinct tickets may be employed such as the series of tickets illustrated in Fig. 3. The tickets may also be printed in strip form and rolled into a compact package for use. It is also an advantage to perforate the stubs whereby they may be easily hung upon a hook or pin as the games are 15 played, said perforation being indicated at 19 in Fig. 1.

20 In accordance with the patent statutes I have described the principles of operation of my invention together with the apparatus which I now consider to represent the best embodiment thereof but I desire to have it 25 understood that the construction shown is only illustrative and that the invention can be carried out by other means and applied to uses other than those above set forth within the scope of the following claims.

30 The "key" which, as described constitutes the serial number printed upon a stub may be variously modified within the spirit 35 of my invention without departing from the principles applied so long as said key is a distinguishing factor by number, word, color or design.

Having described my invention, what I claim as new and desire to protect by Letters Patent is:—

40 1. A game apparatus comprising a series of tickets having marked upon the face of each ticket a group or numbers any one of which in all of the groups may indicate to the person holding it a winning number, all 45 of the numbers of a group being different from any of the numbers in all of the other groups and a key carried by each of the tickets of said series for distinguishing groups of tickets apart constituting a set for 50 playing a game and indicating the game

which is being played, said key being similar on all of the tickets of a single series.

2. A game apparatus comprising a pad having a plurality of leaves and a stub for each leaf detachable therefrom, each leaf of 55 said book comprising a plurality of separable tickets, each ticket being marked with a group of digits, the digits of one group being different from the digit or digits constituting any other group in said series and 60 a key marked on each ticket of said series and upon its stub, said key being similar on all of the tickets constituting a leaf and its stub but different from the key on all of the other tickets and stubs. 65

3. A game apparatus comprising a series of tickets separably connected to a stub having marked upon the face of each ticket a group of numbers any one of which in all of the groups may indicate to the person holding it a winning number, all of the numbers of a group being different from any of the numbers in all of the other groups and a key carried by each of the tickets of said series and by the stub to which a set of tickets is 70 connected for distinguishing groups of tickets apart and indicating to the player the game which is being played, said key being similar on all of the tickets of a single set and the corresponding stub, but different 75 from the key on all of the other tickets and stubs. 80

4. A game apparatus comprising a series of groups of tickets, each ticket of a single group having distinctive symbols printed thereon different from those on all the other tickets of the same group, and a distinguishing key carried by each of the tickets of each group for playing an individual game and indicating the game which is being 85 played, said key being similar on all of the tickets of a single group. 90

In testimony whereof, I have signed my name to this specification, in the presence of two subscribing witnesses.

AUGUST J. KEMPIEN.
